ATTORNEY.

UNITED STATES PATENT OFFICE.

WILLIS H. SANBURN, OF SPRINGFIELD, MASSACHUSETTS, ASSIGNOR TO STRATHMORE PAPER COMPANY, OF MITTINEAGUE, MASSACHUSETTS, A CORPORATION.

PAPER-SIZING APPARATUS.

1,240,154.

Specification of Letters Patent. Patented Sept. 11, 1917.

Application filed September 24, 1915. Serial No. 52,357.

To all whom it may concern:

Be it known that I, WILLIS H. SANBURN, a citizen of the United States of America, and resident of Springfield, in the county of 5 Hampden and State of Massachusetts, have invented certain new and useful Improvements in Paper-Sizing Apparatus, of which the following is a full, clear, and exact description.

10 The object of this invention is to provide a sizing apparatus for paper by means of which the paper drawn from a roll or other supply may be engaged with guides therefor, which form part of the sizing apparatus, and which guides are movable so that in the preliminary engagement the paper is not caused by such guides to be immersed in the sizing liquid, but may be carried in running engagement through the sizing apparatus in its original or dry condition, and so that after having been so carried through, then by the movement of the guides downwardly, the paper is caused to have a course 20 through the sizing liquid.

25 A further object of the invention is to provide an apparatus by means of which the paper may be sized in a better manner, and more properly in accordance with the nature of any given paper and in accordance with the desired character or extent of the sizing thereof, than heretofore.

The invention is described in conjunction with the accompanying drawings and is set forth in the claims.

35 In the drawings:—

Figure 1 is a plan view and

Fig. 2 is a sectional elevation of the sizing apparatus, the parts in section being taken on line 2—2, Fig. 1.

40 Figs. 3 and 4 are respectively a partial side elevation and a partial plan view to more clearly illustrate one of the immersing rolls and the positioning means therefor.

Fig. 5 is a partial elevation for more 45 clearly illustrating means for controlling the action of one set of the squeeze rolls.

Figs. 6, 7 and 8 are diagrammatic views 50 to illustrate some of the innumerable ways in which the web of paper may be carried through the apparatus in accordance with different characters of papers and with different results or effects to be acquired.

In the drawings, A represents an upwardly opening tank for liquid size into

which the size is continuously pumped and 55 permitted to overflow at the forward end so that a substantially uniform height or level of the size is maintained in the tank, as represented by the line α in Fig. 2.

Toward the forward end of the tank is a 60 pair of squeeze rolls B, B, arranged above the liquid level and to run and to be driven in unison, as by means of driving belt and pulley as usual for companion rolls in many classes of machinery.

C and C² represent upper and lower 65 squeeze rolls located intermediately relatively to the length of the tank and adapted to be driven for their coöperation in any usual or approved manner.

The web of paper is run through the sizing machine from a supply roll D, and, after the sizing and squeezing thereof, is guided to and wound upon a take-up roll or reel indicated at E.

70 Means are provided for varying the portion of the running length of the web which is in immersion in the size in the tank.

Moreover, means are provided for causing 75 the emergence of the web from the size in the tank whereby it may be squeezed above the level of the liquid by the intermediately located squeeze rolls C, C², to have the excess size expelled therefrom whereupon it may be caused to have another immersion, 80 and reëmergence in and from the size previous to its final squeezing.

85 Therefore, the apparatus comprises transversely horizontal guide members α and β to the rear of the squeeze rolls C, C² 90 and one or more transverse horizontal guide members δ forward of such squeeze rolls,—such guide members being mounted on movable supports on which any or all thereof may have positions of submersion in the size 95 or elevated positions thereabove.

As here represented, the guide members α , β and δ are constructed as rollers having the opposite journal end portions thereof mounted in the extremities of opposite 100 lever-like arms f which are mounted for partial revoluble movements on opposite sides of the tank.

105 The said lever-like arms f are affixed on transverse shafts g supported in journal brackets f^2 upstanding above the upper edges of the side walls of the tank, each said shaft having at one end thereof means for

its partial revolution, as, for instance, the handle lever *h* formed, in substance, as an extension of the arm *f*.

The handle lever extension *h* is outwardly offset from the roll supporting lever *f* and rigidly connected therewith through the medium of a short transverse shaft *i* and constituting the aforementioned journal for the guide roll supporting arm *f*.

18 The bracket *j* in which combined lever members *f* and *h* are journaled, is made with a series of sockets *k* in circular arrangement, as shown in Fig. 3, and in any of which the locking member *m* carried by 15 the handle lever *h* may engage and disengage.

As indicated, the locking member consists of a screw, having a thread engagement transversely through the handle lever and 20 provided with a head or enlargement, by means of which it may be conveniently manually turned.

With reference to Figs. 2, 6, 7 and 8, some of the many various positionings of the 25 guiding members relatively to each other and to the intermediate and forward sets of squeeze rolls are shown.

In Fig. 6, the partially revoluble guide rolls are shown as swung to their upward positions as done preparatory to the engaging of the running web of paper in its dry condition through the machine; and the intermediate squeeze rolls *C*, *C*² are shown separated.

35 The paper, understood as coming in dry condition from the supply roll *D*, is engaged under the guide rolls *a* and *b*, thence passing over the lower one *C*² of the intermediate squeeze rolls, thence under the guide roll *d*, over the fixed bar or roller *s*², to and between the forward squeeze rolls *B*, *B*, thence passing over the elevated guide *o*, to proceed to the guide *p* and the reel *E*.

The paper easily carried through the apparatus in its dry condition, in its engagement under the rolls *a*, *b* and *d*, as shown in Fig. 6, or in engagement with any one or more of these rolls, may now be caused to have, as it runs, immersion in the liquid in the sizing tank by the downswinging of the revolvably movable roll or rolls with which the paper has its engagement.

In Fig. 7, the paper having been given the running engagements while in dry condition represented in Fig. 6, is by the changed positions of the guide rolls *a*, *b* and *d*, and the lowering of the upper squeeze roll *C*, caused to receive an immersion, a squeezing, another immersion and a final squeezing for a maximum absorption, or saturation and a maximum penetration of the paper by the size.

In Fig. 2, positions of the parts are shown whereby the paper is caused to pass for immersion under the lowered roll *b*, upwardly 65

out from the liquid to pass between the separated squeeze rolls *C*, *C*² and again under the lowered roller *d* and thence to and between the forward squeeze rolls *B* for the result of acquiring a medium penetration 70 of the size in the paper.

In Fig. 8, the paper is carried directly from the supply over the upper squeeze roll *C* which acts as a guide therefor, descending under the lowered guide roll *d*, thence passing over the fixed guide bar or roll *s*² around and between the forward squeeze rolls *B*,—receiving but one dip and but one squeezing with consequently but slight penetration. 75

In Figs. 2, 6, 7 and 8 the relative arrangement of the parts and the manner of utilization of the apparatus with the parts so arranged are those the advantages of which are appreciable to a paper manufacturer, but, as manifest, the apparatus is capable of 80 utilization in different ways other than those shown so far as is concerned the immersion of the paper in the size, extent and duration in which the running length of the paper remains in immersion, and the squeezing or 85 squeezings of the paper whereby the paper is caused to receive size, and to have the size forced by pressure into the web to accord with what may be the desirability or requirement on a run of any particular kind 90 or grade. 95

Either or both sets of the squeeze rolls may have one roll thereof separable relatively to the other roll, and as here shown the upper roll *C* of the intermediately located pair is separable relatively to the lower roll *C*², by means as follows:— 100

The journal bearing members *t* for the upper squeeze roll *C* has rack bars *u* associated, or made as one, therewith. 105

The journal members of the roll *C* have vertical guide ways *v* therefor, formed in the opposite side brackets *v*².

The transverse shaft *w* is provided in suitable journals at the upper part of the 110 brackets *v*², said shaft having a hand wheel *w*² thereon and pinions *w*³, all so that by the turning of the shaft through the hand wheel the roller *C* will be elevated, to leave a clear space between it and the one *C*², or lowered 115 for its pressure bearing in relation to the roll *C*².

For the paper to be sized by immersion and passage through the liquid in the tank *A*, a support comprising a rotative shaft *G* and *S*-shaped members formed by double reversely curved arms *J* *J* on the opposite ends, is provided, said arms having suitable boxes for the end journals of the cores of the supply rolls. 120

By suitable gearing, power driven, the shaft *G* may be rotated as occasion requires so that after a supply roll which had been supported in the upper position shall have become exhausted, the revoluble double- 125 130

armed member may have a half a revolution imparted thereto to bring around another supply roll to the uppermost position.

This arrangement permits always a fresh supply roll to be mounted on what at a given time is the lower pair of arms J, while the paper of the supply roll supported by the upwardly extended pair of arms is being drawn off and caused to travel into, through, and out from the sizing liquid,—the matter of overturning the revoluble support for the positioning of a fresh roll in the place of an exhausted one being a matter of quick performance.

15 The reel or take-up roll E onto which the sized web is wound is mounted in bearings in a supporting frame L forwardly beyond which is a horizontal double trackway M sustained at a proper height by uprights M².

20 The rear end portions of the trackway M M are somewhat forward of the support for the reel so that a space y is open transversely of the machine between the reel and trackway to permit an operative of passing 25 from one side of the machine to the other.

Each trackway comprises double side members r r slightly separated so as to leave space for occupancy therebetween of bridging sections g which may be slid forwardly 30 to have positions as represented by the dotted lines in Figs. 1 and 2 to span the space y and to make the trackway continuous from the reel support to the trackway proper so that when a reel has taken thereon sized paper to its capacity or the extent desired, the reel or core may be displaced from its journal supports and rolled across 35 the trackway sections having the temporary bridging positions and onto and forwardly along the main track, whereupon the bridging sections may be slid forwardly into the rear portions of the main trackway,—leaving transverse space open.

An especially desirable and important 45 capability and advantage of this sizing apparatus accrues from the character of the guides a, b and d, substantially such as exemplified in the drawings and referred to in the description thereof.

50 The paper in its fully or partially dry condition to be sized becomes weak and of slight tensile strength upon being immersed in the liquid size; and it is a matter of ex-

treme difficulty to carry the wet and weakened paper around under guide rods or rolls 55 submerged in the tank; but as pointed out in respect of the position of the parts in Fig. 6, the engagement of the paper in dry condition with some or all of the guide rolls may be performed most quickly and easily 60 and without rupture, and then having been advanced through the forward squeeze rolls to be mechanically advanced thereby, such of the guide rolls a, b, d, etc., are carried in their lowered and submerging positions and 65 so remain during any given run of work.

I claim:

1. In a paper sizing apparatus, an immersion tank, a pair of spaced rollers therein, and means swingingly mounting each roller 70 independently of the other for swinging the roller down into and up out of the tank and toward and away from the companion roller whereby paper passing under said rollers may be immersed varying lengths 75 and at varying depth and dispositions, and squeeze means arranged between said rollers, the latter being adjustable toward and from said squeeze means.

2. In a paper sizing apparatus, an immersion tank, a pair of spaced immersing rollers therein, means swingingly mounting each roller independently of the other for swinging the roller down into and up out of the tank and toward and away from the companion roller whereby paper passing under said rollers may be immersed varying lengths and at varying depth and dispositions, and a pair of coöoperating squeeze rolls 85 toward and from which said immersing rollers are mounted for swinging said squeeze rolls being arranged between the immersing rollers.

3. In a paper sizing apparatus, an immersion tank, coöoperating squeeze rolls mounted thereabove, and an immersing roller 95 swingingly mounted on each side of said squeeze rolls for movement down into and up out of the tank and toward and from the squeeze rolls and each other.

Signed by me at Springfield, Mass., in presence of two subscribing witnesses.

WILLIS H. SANBURN.
